VISUAL SIGNAL TYPE ANNUNCIATOR

Richard H. Campbell, Racine, Wis., assignor to
Webster Electric Company, Racine, Wis., a cor-
poration of Delaware

Application January 5, 1950, Serial No. 136,956

8 Claims. (Cl. 177—329)

1

The present invention relates to annunciators and more particularly to annunciators of the visual type which are particularly well adapted for use with intercommunication apparatus.

As will be understood by those skilled in the art, annunciators have numerous applications. They are, for example, extensively employed in connection with intercommunication apparatus to indicate by visual and/or audible means to the called party, not only that such party, for example, is being called, but also to designate the calling party. Preferably, the signal produced by such annunciators should remain effective until the calling party has taken some positive steps in answering the call. It has been customary, for example, in connection with such intercommunication apparatus, to provide selective switching means whereby the called party may select and complete the communication circuit with the calling party as determined by the annunciator which is operative. It would be desirable to terminate the signaling operation of the annunciator concurrently with or following such positive action. Numerous types of annunciators have been suggested heretofore. All of these prior arrangements, however, have been complicated and have not lent themselves favorably to loudspeaker type intercommunication apparatus.

Accordingly, it is an object of the present invention to provide a new and improved annunciator system.

Still another object of the present invention resides in the provision of an improved annunciator of the visual signal type particularly well adapted for use with intercommunication equipment.

It is another object of the present invention to provide an annunciator in the form of a sub-assembly whereby any reasonable number of them may be applied to a unit or device merely by supporting the subassembly from the device.

Still another object of the present invention resides in the provision of a compact annunciator which may fit into a very small space so that large numbers of them may be associated with a small cabinet or housing.

Further objects and advantages of the present invention will become apparent as the following description proceeds and the features of novelty which characterize the invention will be pointed out with particularity in the claims annexed to and forming a part of this specification.

For a better understanding of the present invention reference may be had to the accompanying drawing in which:

2

Fig. 1 is a fragmentary perspective view of an embodiment of the annunciator of the present invention shown associated with a portion of an intercommunication system.

Fig. 2 is a schematic circuit diagram illustrating an application of the annunciator of Fig. 1; and

Fig. 3 is a somewhat perspective view of a portion of a station illustrating how a plurality of annunciators of the present invention may be associated therewith in a small compact arrangement.

The present invention is generally concerned with the details of a visual signal type annunciator for use with intercommunication apparatus in which, for example, the annunciator is rendered effective by a partly located at a point remote from the annunciator wishing to communicate with the party located adjacent the annunciator. The annunciator includes a suitable signal light which is preferably continually energized whenever the unit of the intercommunication apparatus is rendered operative as by supplying power thereto. The annunciator further includes an aperture through which light rays from the signal may be directed. In addition, means for modifying the rays from this signal light directed toward the aperture are provided in the form of a movable member normally disposed in a predetermined position corresponding to the ineffective condition of the annunciator. By means of a suitable electromagnet energized through action of the calling party, the means for modifying the light rays is rendered effective with the result that the visual signal produced by the annunciator indicates to the called party that he is being or has been called by a particular calling party. This signal remains effective until some action is taken on the part of the called party to complete an intercommunicating circuit between the called and calling stations.

For a better understanding of the present invention, reference may be had to the accompanying drawings in which the annunciator of the present invention is generally designated by the reference numeral 10 in Fig. 1 of the drawing. It will be understood that the annunciator of the present invention has numerous applications. In order to aid in understanding the operation of the annunciator of the present invention, it has been illustrated in connection with an intercommunication system generally designated at 11 in Fig. 2 of the drawing. Intercommunicating apparatus such as might be employed for inter-office communication or the like, comprises a plu-

rality of stations designated in Fig. 2 by the reference numerals 12, 13, 14, etc. Appropriate nomenclature such as station 1, station 2, station 3, etc., has been applied to the individual units as a further aid in understanding the operation of the annunciator per se with which the present invention is particularly concerned. Conventionally, each station of an intercommunicating system may include, in addition to the annunciators, a loud speaker, selectively operable communication controlling means, station selector means and the like. Generally, each station includes a unit or device which is usually disposed in a position where it may readily be seen, comprising a suitable cabinet or housing 15 on the front panel of which may be located a plurality of manually operable station selector control means designated as 16a, 16b, 16c and 16d respectively, each of which preferably has an operative portion extending within the cabinet 15, as through suitable apertures 17a, 17b, 17c and 17d respectively. By way of example only, the unit illustrated in Fig. 3 of the drawing is shown capable of being used with four additional stations to provide a five station system. Each station has as many annunciators as there are stations which can call a particular station in the system, i. e., one less annunciator than the number of stations in the system. This indicates the need for compact annunciators when used in a multiple station intercommunication system, if it is desirable as usually is the case, to maintain the cabinet or housing 15 at each station as small as possible.

As illustrated, each of the selector means 16 has associated therewith an annunciator 10 forming the basis of the present invention which exteriorly of the cabinet 15 appears only as a windowed aperture 18. As illustrated in Fig. 3 of the drawing, four apertures 18a, 18b, 18c and 18d are provided, one associated with each selector element 16 marked with the corresponding subscript. These apertures are capable of being illuminated by a visual signal means in a predetermined manner described hereinafter so as to indicate which station is calling. If desired, suitable indicia shown in Figs. 1 and 3, such as the names of the parties at the different stations, may appropriately be associated with the apertures 18, so that when the annunciator associated with a particular aperture 18 is rendered effective, the called party will know at a glance who is calling or has called him.

The selector means 16 are preferably station selector switches designated by the same reference numerals in Fig. 2 as in Fig. 3. As illustrated, these switches comprise a manually actuatable member which may be moved either to the right or to the left as viewed in Fig. 3 and in either position being capable of operating certain control circuits. In Fig. 2 of the drawing some of the circuits for the selector switches 16a and 16b are indicated. As illustrated, each of the switches has associated therewith two sets of switches each having normally open contacts designated as 20a and 21a respectively for the selective control means 16a. The contacts 20a are illustrated as controlling a communication circuit between stations 1 and 2. The contacts 21a, on the other hand, are capable of completing a calling circuit whereby station 1 may call station 2. Similarly, selective control means 16b includes switches comprising contacts 20b and 21b for completing the communication circuit between stations 1 and 3, and calling station 3, respectively.

Considering now the improved annunciator of the present invention, reference may be had to Fig. 1 where the apertures 18a and 18b are visible and the selector switch 16a may be seen to comprise manually movable member 22 pivoted to means associated with the cabinet 15 as indicated at 22a, so that a portion thereof extends through the aperture 17a for actuation from outside the cabinet. The contacts 20a and 21a are not visible in Fig. 1 of the drawing but the resilient supporting arms for these contacts are generally designated by the reference numeral 23. These arms 23 are mounted in spaced insulated relationship by means comprising a plurality of insulators 25 which in turn are supported on an angularly disposed flange 24a of an L-shaped bracket 24 having one arm of the L attached to the inside front panel of the cabinet 15. As illustrated, said one arm of the bracket 24 has an aperture 26 therein which is aligned with the aperture 17a. Preferably the member 22 is pivoted to the bracket 24 whereby the annunciator 10 may comprise a subassembly of parts all mounted on the bracket 24. The end of member 22 disposed within the cabinet 15, is effective to move the resilient contact arms 23 selectively to close the contacts 20a or 21a or, if desired, others not shown in the drawing.

In accordance with the present invention, a suitable light source 28 connected to a source of electrical energy is disposed so that rays of light therefrom are directed to each of the apertures 18a, 18b, 18c and 18d. These apertures are preferably covered with an uncolored translucent material so as effectively to provide a translucent window upon which the indicia referred to above may be imprinted. The signal light 28 is preferably energized whenever the power supply unit for the particular station of the intercommunicating apparatus is energized. Consequently, this light shining through the apertures 18 additionally serves to indicate that the intercommunicating apparatus is ready for use should it be required.

For the purpose of producing a signal at the front of the cabinet 15 indicative of the particular annunciator operated, the annunciator subassembly comprises in accordance with the present invention, a colored transparent or light permeable movable member or flag 30, preferably formed of a suitable plastic or the like, pivotally mounted as indicated at 31 to suitable pivot supporting arms 32a forming part of a support 32 either detachably or permanently attached to the bracket 24. This flag member 30 is adapted to move to a light ray modifying position overlying the windowed aperture 18a so that when in this overlying position, a colored light, the color determined by the particular transparent flag employed, appears at this aperture to indicate annunciator operation.

For the purpose of causing the flag 30 to tend to move into its operated position there is provided a spring 33 connected to a lever arm extension 30a of the flag 30. Normally, the flag 30 is held in a predetermined position remote from the associated aperture 18a, and for this purpose there is provided a suitable latching arm 35 also pivotally mounted as indicated at 36 to suitable extensions 32b of the support 32. The latching arm 35 is provided with a hook-shaped latching finger 35a for engaging the free end of the flag 30. The latching finger 35a is provided with a cam surface 37 to permit relatching of the flag. It should be noticed that the latching arm 35 is

continually biased to its latching position by the same spring 33 which tends to bias the flag 30 into its operated position.

In accordance with the present invention, the latching arm 35 is constructed as a sort of a bell-crank with a laterally disposed lever arm 39 extending in a direction generally parallel to an arm of the L-shaped bracket 24 so as to bring it into operative relation to a plunger 40 of an electromagnet 41 suitably supported from the support 32 and extending through an aperture 24b in the bracket to above the arms 23. The support 32 is also provided with an aperture 32c to permit the plunger 40 to operate lever arm 39 as illustrated. The winding of this electromagnet is schematically designated in Fig. 2 of the drawing by the reference numeral 42a, and correspondingly the winding of the electromagnet associated with the selector control means 16b is designated as 42b.

Winding 42a at station 1 is connected in an electrical circuit with the contacts 43 of a selector switch at station 2 and in series with a source of power schematically indicated as a battery 44. It will be apparent that momentary closure of the contacts 43 by operation of a selective control means, which may be similar to the means 16a at station 1, will cause winding 42a to be energized with the consequent movement of the plunger 40 in a direction to release the latching arm 35 with the result that the spring 33 is effective to move the flag 30 to its operated position. In similar manner, the winding 42b is connected in an electric circuit with the contacts 44a and a source of potential 45 located at station 3.

With the annunciator employed in an intercommunicating system, its operation as just described will indicate to the party at station 1 that he is being or has been called by the party at station 2 and by manipulating selector switch 16a to close the contacts 20a, which would require rotation of member 22 in a counter clockwise direction as viewed in either Figs. 1 or 2, there is completed a communication circuit between stations 1 and 2. Under these conditions it will be understood that it is desirable to restore the annunciator to its non-indicating position and in accordance with the present invention, the lever extension 30a of the flag 30 is connected by a suitable link 46 with the selective control means 16a, and preferably to member 22, the link extending through aperture 24a or, if desired, through a separate aperture individual to it. Rotation in a counterclockwise direction, as viewed in Fig. 1 of member 22, causes the flag 30 to return to the position shown in Fig. 1. In order that the link 46 not interfere with free operation of the flag 30 in response to energization of the electromagnet 41, the link is constructed with a lost motion connection, which may comprise a loop portion 46a, with pin 47 on member 22. This connection also enables member 22 to be operated to close the signaling circuit without operating the annunciator.

In order that the party at station 1 may call the party at station 2, the contacts 21a are connected in circuit with a source of potential 48 and a winding 49 of an electromagnet forming part of an annunciator located at station 2 70 preferably identical with the annunciator 10. Similarly the contacts 21b are connected in circuit with a source of potential 50 and a winding 51 of an electromagnet forming part of an annunciator located at station 3.

In view of the detailed description included above, the operation of the annunciator of the present invention will readily be understood by those skilled in the art. Under normal conditions when the intercommunicating apparatus with which the present invention has been illustrated by, is not being used, the flag 30 is latched in the predetermined position shown in Fig. 1 which may be designated as the annunciator off position. Upon the energization of the electromagnet 41, the latching arm 35 is actuated to free the flag 30 which, under the bias of the spring 33, moves to its operated position. Since the flag 30 is formed of a colored transparent material such as colored glass or a colored plastic, the rays of light from the source 28 directed through this flag will give a clear indication of annunciator operation. The annunciator is restored to its normal operation upon actuation of the station selector switch 16a.

From the above description it will be apparent that there has been provided an annunciator assembly mounted on either side of a bracket 24 which furthermore may have sufficient length to support additional identical or similar annunciators in a compact arrangement. The members 30, 35 and 33 and electromagnet 41 furthermore comprise an assembly attachable to one side of the bracket 24 while the contact arms 23 are effectively supported at the other side below the electromagnet, which extends through the bracket. The link 46 can be attached upon final assembly of the parts.

While there has been illustrated and described a specific embodiment of the present invention which is especially adapted for use in intercommunication apparatus, it will be understood by those skilled in the art that numerous changes and modifications may be made, and it is aimed in the appended claims to cover all such changes and modifications as fall within the true spirit and scope of the present invention.

What is claimed as new and desired to be secured by Letters Patent of the United States is:

1. In an annunciator of the visual signal type comprising a housing having an aperture, a movable signal member normally disposed in a predetermined position and movable relative to said aperture, means including an electromagnet capable of being energized to operate said annunciator, means operatively interconnecting said electromagnet and signal member whereby energization of said electromagnet effectively causes movement of said member from said predetermined position, and means including a manually actuatable control element and a lost motion linkage element operatively connected to said control element and said movable signal member operable after operation of said annunciator for restoring said signal member to said predetermined position.

2. In an annunciator of the visual signal type comprising a housing having an aperture, a movable signal member normally disposed in a predetermined position and movable relative to said aperture, means including an electromagnet and an armature operable thereby for operating said signal member, means operatively interconnecting said armature and member whereby energization of said electromagnet effectively causes movement of said member from said predetermined position, and means including a manually actuatable control element and linkage means operatively connected to said control element and said movable member operable after opera-

tion of said annunciator for restoring said movable member to said predetermined position, a support, means supporting said electromagnet and control element at one side of said support, and means supporting said signal member at the other side of said support, and said linkage means and armature extending across said support.

3. In apparatus of the type described, a housing having spaced apertures, a first for a signaling member and a second for a station selector operating member, a generally L-shaped support inside said housing located with its shorter leg to one side of said first aperture and provided with a second aperture aligned with the second aperture in said housing, the longer leg of said support extending rearwardly of the housing, a movable signal member mounted in operative relation to said first aperture and movable relative to said aperture from a predetermined position, station selector switch means mounted to the rear of the shorter leg, a switch operating member extending through said second apertures, an electromagnet mounted above said switch means and capable of being energized to operate said signal member, means extending through said support and operatively interconnecting said electromagnet and signal member whereby energization of said electromagnet effectively causes movement of said member from said predetermined position, and means including a lost motion linkage element extending through said support and operatively connected to said switch operating member and said signal member for restoring said signal member to said predetermined position.

4. In apparatus of the type described, a housing having two vertically arranged series of horizontally spaced apart apertures, the first series being for signaling members and the second for station selector switch means operating members, a generally L-shaped vertically extending support inside said housing located with its shorter leg to one side of said first series of apertures and provided with a series of apertures aligned with the said second series of apertures in said housing, the longer leg of said support extending rearwardly of the housing, movable signal members mounted in operative relation to each of said first apertures and movable relative to said apertures from predetermined positions adjacent thereto, a vertically arranged series of selector switch means mounted on the longer leg and to the rear of the shorter leg, switch operating members extending through said second apertures, an electromagnet mounted above each of said switch means and capable of being energized to operate said signal member, means extending through said support and operatively interconnecting each electromagnet with its associated signal member whereby energization of the electromagnet effectively causes movement of the member from its predetermined position, and means including a lost motion linkage element extending through said support and operatively connecting each switch operating member and its associated signal member for restoring the signal member to its predetermined position.

5. In an annunciator of the visual signal type comprising a source of light adapted to be normally energized, a housing having an aperture through which light rays from said source may be directed to produce a visual signal indication, means for controlling said aperture to modify the rays from said source passing through

5 said aperture comprising a pivotally mounted light permeable member movable between a first position overlying said aperture and a second position remote from said aperture, latching means for normally maintaining said member in said second position, means for biasing said member towards said first position, an electromagnet, means operatively interconnecting said electromagnet and said latching means whereby energization of said electromagnet releases said latching means and permits said member to move from said second to said first position, a manually actuatable control element associated with said annunciator, and means responsive to operation of said control element following operation of said annunciator for moving said member from said first to said second position.

6. In combination with a supporting means having an aperture, an annunciator of the visual signal type comprising a visual signal member, means for supporting said member for movement between a first position overlying said aperture and a second position remote from said aperture, latching means for normally holding said member in said second position, a single spring means for simultaneously biasing said member toward said first position and said latching means toward said latching position, an electromagnet, means operatively interconnecting said electromagnet and said latching means whereby energization of said electromagnet releases said latching means and said spring means causes said signal member to move from said second to said first position, and manually operable means including a lost motion connection for moving said signal member from said first to said second position and resetting said latching means.

7. In combination with a supporting means having an aperture, an annunciator of the visual signal type comprising a visual signal member, means for supporting said member for movement between a first position overlying said aperture and a second position remote from said aperture, latching means for normally holding said member in said second position, a single spring means for simultaneously biasing said member toward said first position and said latching means toward said latching position, an electromagnet, means operatively interconnecting said electromagnet and said latching means whereby energization of said electromagnet releases said latching means and said spring means causes said signal member to move from said second to said first position, manually operable means including a lost motion connection for moving said signal member from said first to said second position and cam means on said latching means cooperating with said signal member for relatching it in said second position in response to operation of said manual means.

8. A station selector switch and annunciator means including a support having an apertured wall, a station selector switch at one side of said wall and secured thereto, switch operating means located at said one side of said wall for said station selector switch, an electromagnet located at said one side of the wall and having a movable armature extending through said wall, visual annunciator operating means mounted upon and at the other side of said wall and operatively associated with said armature, visual signal means controlled by said visual annunciator operating means, and visual signal restoring means extending through the

wall operatively interconnecting said visual signal means and said switch operating means.
